ATTORNEY

Patented Jan. 11, 1927.

UNITED STATES PATENT OFFICE.

JOSEPH F. C. LUHAN, OF NEW YORK, N. Y.

SANITARY DISPENSER FOR PLASTIC MATERIALS.

Application filed August 4, 1925. Serial No. 48,028.

My invention relates to sanitary dispensers for plastic materials, of the general type in which a tube of pasty material is detachably mounted within a container so arranged that pressure may be applied to the tube from time to time to force out the material as required.

More particularly stated I seek to provide a device of this character in which there is a minimum of mechanical parts, arranged in the interest of simplicity and of such form that they are each at all times readily accessible. One purpose of my invention is to so form and arrange the container that 15 the paste tube with its cap removed merely screws into position within the container, the latter being provided with a cap of its own. By this arrangement the parts including the tube of paste, are fitted together quite substantially and in a form in which the device 20 as a whole can be readily handled without disturbing the relative positions of the parts.

Reference is made to the accompanying drawing forming a part of this specification, 25 and in which like reference characters indicate like parts throughout all of the figures.

Figure 1 is a side view, partly an elevation and partly a section, showing one form 30 of my device, and indicating how it operates.

Figure 2 is a side elevation of the form of my device appearing in Figure 1, the casing cap being in position, and indicates by dotted lines the manner in which the casing 35 walls can swing apart.

Figure 3 is a fragmentary elevation showing another form of my device, the container being closed.

Figure 4 is a fragmentary elevation of the 40 mechanism appearing in Figure 3, the container being open.

In the form appearing in Figures 1 and 2, a casing container head appears at 5 and has a form approximating that of a small 45 saucer. A pair of container walls 6, 6, each of substantially semi-cylindrical form, are connected with the container head 5, by means of hinges 7, and are thus journaled upon the container head.

50 The walls 6, 6, may be swung apart, as indicated by dotted lines in Figure 2 and brought back into their normal positions indicated by full lines in said figure.

A cap 8 is adapted to fit detachably upon 55 the lower end of the container so as to en-

close the lower ends of the two casing walls 6, 6. This cap carries a pair of spacers 9, which may be conveniently formed out of sheet metal, and in this instance have the form of tongues, extending from the edge of 60 the cap and bent back upon themselves. These spacers are held upon the cap 8 by soldering or brazing.

The parts are so formed and arranged that with the container walls 6 occupying 65 their normal positions as indicated by full lines in Figure 2, they press against opposite edges of the spacers 9. There is thus virtually formed between the casing walls a pair of longitudinal slots, exactly alike, one 70 of which appears at 10 in Figure 2.

The container head 5 carries a nozzle 11, integral with it as shown more particularly in Figure 1. This neck 11 is provided internally with a thread 12 and externally with 75 another thread 13. A cap 14 is threaded internally and fitted upon the neck 11, the threads of the cap engaging the threads 13.

A tube 16, containing the plastic material to be dispensed, is of the general form 80 generally well known in this art, and is compressible in the usual manner for the purpose of ejecting its contents. A key 17, provided with a handle 18, is secured to the tube 16, and by turning the handle 18 the 85 adjacent portion of the tube is wound upon the key in the form of a roll 19.

The tube 16 is provided as usual with a nozzle 20, threaded externally as shown in Figure 1. With the device in action, the 90 handle 18 is turned slightly by the operator, and the paste or other plastic material contained with the tube 16 is ejected as indicated by 21.

As the material is gradually used up, the 95 handle 18 is turned progressively until the tube is empty. In order to replace the tube the operator removes the cap 8 and swings the container walls 6, 6 apart, as indicated in Figure 2, and then grasps the tube and 100 turns it relatively to the casing. This disengages the threaded nozzle 20 from the nozzle 11 carried by the head 5. To replace the tube with a new one the cap of the tube is removed, the tube inserted in the 105 container, and the tube is turned by hand sufficiently to fit the threaded nozzle 20 into the neck 11.

One of the casing walls 6 is provided 110 with two holes 6^a to be used in mounting

the container permanently upon a fixture such as a wash basin, bathroom wall or the like should this be desirable.

In the form of my device appearing in Figures 3 and 4 the container cap is shown at 22 and the container walls appear at 23, 23, being journaled upon the cap 22 by hinges, one of which appears at 24.

The space between the container walls 23, 10 23 thus constitutes a slot 25. Except as just described the form of my device appearing in Figures 3 and 4 is identical with that shown in Figures 1 and 2.

My improved dispenser, containing a tube 15 of plastic material and in actual practical use, constitutes a valuable time saver. The operator always finds the various parts of the container fixed firmly in position relatively to each other, no part being loose, and 20 no movable part requiring to be adjusted or brought back to a predetermined position. And then when the tube of plastic material is used up, another tube can be substituted in a moment and is ready for 25 use.

If the operator desires to close the tube he does so by simply screwing the container cap 14 upon the neck 11. He can do this very quickly.

30 The device is economical as regards the plastic material, and is absolutely sanitary. It is made up of parts easily standardized, and requiring a minimum of work in manufacture. Altogether the device is suitable 35 for manufacture in large quantities.

Having thus described my invention what I claim as new and desire to secure by Letters Patent is as follows:

1. A sanitary dispenser for plastic mate-

rials, comprising a container head provided with a neck, a pair of cylindrical walls journaled upon said container head and adapted to swing apart in order to permit the entrance and removal of a tube of plastic material, said neck being provided with means for securing the nozzle of a tube enclosed within the container so as to hold said head and said tube independently of the swinging of said walls.

2. A sanitary dispenser for plastic materials, comprising a container head provided with a neck, a pair of cylindrical walls journaled upon said container head and adapted to swing apart in order to permit the entrance and removal of tubes of plastic material, said container head and said walls being of proper form to enclose a tube of plastic material, said neck being threaded internally to fit the threaded nozzle of a tube enclosed within the container.

3. A device of the character described comprising a container head provided with a neck extending therefrom and threaded internally, casing walls journaled upon said casing head and formed for enclosing a tube of plastic material, said neck being formed to fit upon the nozzle of said tube of plastic material, a cap for fitting over the ends of said walls and spacers carried by said cap and having the form of tongues extending from the edge thereof, said tongues extending between said walls for the purpose of spacing said walls apart.

Signed at New York city, in the county of New York and State of New York, this 75 31st day of July, 1925.

JOSEPH F. C. LUHAN.
